Primary Examiner — David G Muller*Assistant Examiner* — Nathan M Johnston*(74) Attorney, Agent, or Firm* — Kim Winston LLP(57) **CLAIM**

The ornamental design for a wearable autoinjector, as shown and described.

DESCRIPTION

FIG. 1 is a top plan view of a wearable autoinjector showing our new design;

FIG. 2 is a bottom plan view thereof;

FIG. 3 is a left side elevation view thereof;

FIG. 4 is a right side elevation view thereof;

FIG. 5 is a rear elevation view thereof; and,

FIG. 6 is a front elevation view thereof.

The dot dash lines illustrate portions of the wearable autoinjector which form no part of the claimed design.
